ATTORNEY.

UNITED STATES PATENT OFFICE.

EDWARD COX, OF BLOOMFIELD, IOWA, ASSIGNEE OF ONE-FOURTH TO EDWARD N. BEZZENBERGER, OF BLOOMFIELD, IOWA.

POULTRY CRATE

Application filed January 29, 1921. Serial No. 441,001.

To all whom it may concern:

Be it known that I, EDWARD Cox, a citizen of the United States, residing at Bloomfield, in the county of Davis and State of Iowa, have invented certain new and useful Improvements in Poultry Crates, of which the following is a specification, reference being had to the accompanying drawings.

This invention relates to improvements in poultry crates and more particularly to a device of this character which is collapsible.

An important object is to provide a device of this character which when in the extended position is very rigid in structure and which may be flatly folded for shipment when empty.

A further object of the invention is to provide in a folding crate, members which hold portions of the crate when the crate is in extended position to prevent shifting thereof and which serve as a locking means for holding the crate in the collapsed position.

Other objects and advantages of the invention will become apparent throughout the course of the following description.

In the accompanying drawings, wherein for the purpose of illustration is shown a preferred embodiment of my invention and wherein like reference characters designate like parts throughout,

Figure 1 is a plan view of a crate constructed in accordance with my invention showing the same in extended position and ready for use,

Figure 2 is a side elevation thereof,

Figure 3 is an end elevation thereof,

Figure 4 is a section on the line 4—4 of Figure 1,

Figure 5 is a sectional view through the crate when in the folded position, the section being taken on the line 5—5 of Figure 6, and

Figure 6 is a plan view of the folded crate.

Referring now more particularly to the drawings, the numeral 10 indicates a rigid base which may be formed of any desirable material. This base has secured to its upper surface at the ends thereof transversely extending guide plates 11, each having formed therein a pair of slots 11^a parallel to the base and having their adjacent ends separated by an integral portion 11^b of the plate arranged centrally of the plate.

The numeral 12 indicates a reticulated top structure which is formed of spaced transversely extending cross members 13 and lon-

gitudinally extending members 14. The center of the top 12 is preferably provided with a sliding door closure D.

Certain of the transversely extending members 13 are continued at the sides of the top 12 and bent downwardly and provided at their lower ends with loops 15 which pivotally receive therein the upper strands 16 of side members S. These side members S have the lower strands 17 formed of relatively heavy material, and these strands 17 are of greater length than the side members and have their end portion 17^a projecting into the grooves 11^a of the guide plates 11, and slideable therein. The ends of the upper strand member 16 of the side members are bent downwardly and secured to the lower strand 17 and combine therewith to form the support for a reticulated structure forming the side member proper. The side members S are of less than one-half the width of the top member 12 so that the side members may fold beneath the top members without overlapping.

End members 19 are provided, pivotally connected to the end transverse members 13 at opposite ends of the top 12 by means of loops 20 formed upon the upper ends of the side strands 21 of the end members 19. The side strands 21 have secured thereto the horizontal strands 23 to which are secured the vertical strands 24, these vertical strands having their lower ends secured to the lower strand 22. To a transverse strand 13 adjacent each end of the top is pivotally connected a gravity latch member 25. Each of these members embodies a cam section 26 adapted to be engaged by one of the transverse or horizontal members 23 of its adjacent end member 19 when the same is swung inwardly and upwardly so as to force the latch to swing about its pivot and permit the strand 23 to be received on a shoulder 27 of the latch, so that the end member 19 may be supported in elevated position. Extending transversely of the base 10, approximately centrally thereof, is a member 28 provided upon its ends with the resilient hook portions 29 with which the strands 17 are adapted to engage when the strands 17 are moved outwardly in the slots 11^a, the hook portions 29 engaging the strands 17 to resiliently oppose their return movement toward the inner ends of the slots.

When it is desired to fold the coop the end

members 19 are folded inwardly so that they are engaged by the hook members 25 and held in elevated position. When the end members are in this position the side members 5 are free to swing about their pivots as the spacing of the upper edge of the door from the top 12 of the downturned portions of the transverse members 13 provides a storage space for the end members. 10 Pressure being placed on the top of the coop the strands 17 slide inwardly in the slots 11^a toward the inner ends thereof and the top 12 accordingly approaches the base. As the top approaches the base a strand 16 of each 15 of the end members engages the outer faces of the hooks 29 causing the hooks to move inwardly. As the top strands 16 pass the bulge of the outer face of the hook, these hooks again spring outwardly holding the 20 strands 16 between the hooks and the base. Since these strands are firmly secured to the top member, movement of various members of the crate is effectually prevented.

From the foregoing it will be obvious that 25 I have constructed a collapsible shipping crate for use in shipping fowl which is particularly well adapted for use by reason of the fact that the same may be readily collapsed when not in use and by reason of the 30 fact that parts thereof cooperate to provide a rigid structure both when the crate is in use and when the same is folded. It will furthermore be obvious that the construction as hereinabove set forth is capable of some 35 change without materially departing from the spirit of my invention, and I accordingly do not limit myself to such specific structure except as hereinafter claimed.

What I claim is:

40 1. In a collapsible poultry crate, a base, transverse guides secured to said base adjacent the ends thereof and having pairs of slots formed therein substantially paralleling said base, a top member, side members

pivotaly connected with said top member 45 and each embodying upper and lower strands, said lower strands being of greater length than said side members and having their ends slidably mounted in the slots of said guide members, end members pivotaly 50 connected to the top member intermediate said side members and common means engaging the lower strands of said side members when the crate is in extended position to hold the lower ends of the side members 55 against shifting, and engaging the upper strands of said side members when the crate is collapsed to hold the crate in collapsed position.

2. In a poultry crate, a base, transverse 60 guides secured to said base adjacent the ends thereof and having pairs of slots formed therein substantially paralleling said base, the inner ends of said slots being disposed substantially centrally of the guide 65 members, a reticulated top member comprising transverse and longitudinally extending strands, side members each embodying upper and lower strands, certain of the transverse strands of the said top member 70 being extended downwardly at the sides thereof, loops formed on the lower ends of said last named transverse members and pivotally engaged with the upper strand of said side members, the lower strands of 75 said side members being of greater length than said side members and having their lower ends slidably mounted in the slots of said guide members, end members pivotaly connected to said top member intermediate said side members, said guides limiting the outward swing of said end members and means engaging said end members when the same are swung inwardly for holding the end members in elevated position. 80

In testimony whereof I hereunto affix my signature.

EDWARD COX.
